UNITED STATES PATENT OFFICE.

CLINTON L. BOPP, OF WATERLOO, IOWA.

WIRELESS AUTOMATIC RAILWAY REGISTERING SYSTEM.

1,213,066.

Specification of Letters Patent. Patented Jan. 16, 1917.

Application filed February 24, 1913. Serial No. 750,426.

To all whom it may concern:

Be it known that I, CLINTON L. BOPP, citizen of the United States, residing at Waterloo, in the county of Blackhawk and State 5 of Iowa, have invented certain new and useful Improvements in Wireless Automatic Railway Registering Systems; and I do hereby declare the following to be a full, clear, and exact description of the invention, such as will enable others skilled in the art to which it appertains to make and use the same.

This invention relates to block signaling systems, and one object of the invention is 15 to provide means at the end of each block and at other designated points for indicating the name of the station which a given train is passing and also for indicating the number of the next train to pass that station.

Another object of the invention is to provide a block signaling system actuated by suitable mechanism carried by the locomotives of the trains passing over the system 25 but where there is no contact made between the circuits along the track and the locomotive circuit.

A further object of the invention is to provide a block signaling system wherein the 30 signals are transferred from the moving locomotive to local circuits at the end of each block by means of wireless telegraphy, these local circuits communicating with a line wire which runs throughout the length 35 of the system.

A still further object of the invention is to provide a block signaling system with wireless telegraph apparatus for taking up a signal and a short insulated track section 40 adjacent the wireless apparatus, the said wireless apparatus operating only when the moving train is passing over the insulated track section.

With these and other objects in view the 45 invention comprises certain novel constructions, combinations, and arrangements of parts as will be hereinafter more fully described and claimed.

In the drawings: Figure 1 shows the 50 circuits which are stationary along the system at station 1. Fig. 2 shows circuits similar to those in Fig. 1, but located at station 2. Fig. 3 is a diagrammatic view of the Hertzian wave generating apparatus carried by the locomotive.

I am aware that it has been proposed

to use wireless telegraphy for use in block signaling systems, and also for communicating between trains or ships at sea, but these systems have required that the message be sent for a considerable distance through the medium of the ether. I am also aware that some of these wireless signaling systems are designed to be used in connection with wires or metallic conductors running along the line of traffic, these metallic conductors in some cases being insulated at the ends of the blocks. These metallic conductors, however, do not act to transfer the actual signaling current from one block to another, but serve only as a means for directing the wireless waves which are set up by the Hertzian wave generating apparatus.

In the present instance, I propose to use 75 the ordinary telegraph apparatus and also a wire or other metallic conductor strung along the path of traffic, but the metallic conductor in this present instance does not serve to direct the Hertzian waves but 80 serves to transmit comparatively low potential current from one block to another, the conditions upon which the current is transferred being dependent upon the proximity of the wave generating set on the 85 train to the wireless apparatus located at the end of the block. Generally, this object is obtained by having a short insulated track section located at the end of each block and in also having wireless apparatus 90 adjacent the insulated track section which is adapted to be energized when the moving train comes within a distance of the apparatus which is not greater than the 95 length of the insulated track section. Local circuits closed by the wireless apparatus then transmit the signal to the next station by means of the metallic conductor.

In the drawings but one specific arrangement is shown for accomplishing my desired 100 results, and referring more particularly to Fig. 3, which illustrates the apparatus to be carried by the moving train, it will be seen that there is provided a suitable source 1 of alternating current shown here as a 105 generator which may be driven by any suitable mechanism carried by the locomotive. Connected across the generator is a suitable condenser 2, the circuit for which condenser may be broken by means of a manually 110 operated switch 3. Connected in parallel with the condenser 2 is a primary 4 of a

suitable induction coil, while the secondary 5 of the induction coil is connected to suitable means 6 for defining the spark gap. One side 7 of the means for defining the spark gap is 10 electrically connected to the ground, while the other side is connected to a suitable antenna 8. While the source of current 1 has been shown as an alternating current generator, yet it is to be understood, of course, that any means can be provided for 15 producing either an alternating or a pulsating current in the primary 4 of the induction coil, and further that such changes in the condenser, length of spark gap, and antenna, may be made as will be found necessary in any particular set of operating conditions.

By means of the structure so far described it will be seen that when switch 3 is closed 20 a spark will pass across the spark gap, said spark being effective in setting up waves which emanate from the antenna. The spark is designed to be of such strength as to be effective over a comparatively small 25 area, the dimensions of this area being described more completely hereinafter.

Referring now more particularly to the stationary circuits and apparatus which are connected at the end of each block and which 30 are shown in Figs. 1 and 2, where the conditions are shown as transmitting a signal from station 1 to station 2, it will be seen that the railway track is provided with an insulated section comprising parallel members 8 and 9 mounted in any suitable way. An antenna 10 is connected by means of a wire 11 to a coherer 12, which coherer 12 is connected by means of a wire 13 to the ground. While I have shown a coherer as 35 one specific means or apparatus for detecting the passage of very minute currents in the antenna, yet it is to be understood that I may use any of the many forms of detectors which are known and used in wireless telegraphy. As the locomotive carrying the Hertzian wave generating set approaches but is still distant from the insulated track section, the waves set up by the said apparatus will not be sufficiently strong to 40 reduce the resistance of the coherer sufficiently for local current to pass therethrough, but when the locomotive enters upon the insulated track section the waves emanating from the locomotive will have become strong 45 enough to cause the coherer to respond, and there will be set up sufficient current in the antenna to break down very materially the resistance of the coherer, these actions being well understood by those familiar with 50 the art of wireless telegraphy. When current has passed through the coherer 12 and has reduced the resistance thereof, current 55 will pass in a local circuit from the ground, through wire 14, electro-magnet 15, wire 16, battery 17, impedance coil 18, wire 19, co-

herer 12, wire 13, and return to the ground. The impedance coil 18 is for the purpose of forcing high potential current from the antenna through the coherer and preventing the discharge thereof to the ground without 70 passing through said coherer. Current flowing in the circuit just described will energize electro-magnet 15, which energization will result in the raising of armatures 20 and 21, which will close respectively contacts 22 and 23.

When electro-magnet 15 is energized and armature 20 is contacted with contact 22, a circuit will be completed from the ground at station 1 through wire 14, armature 20, contact 22, wire 24, wire 25, wire 26, electro-magnet 27, wire 28, where the current divides, part going to electro-magnet 29, wire 30, binding posts 31, wire 32, to the main line 33 at station 1; thence to binding post 4^a at station 2, 85 wire 33, wire 28', electro-magnet 29', wire 30', binding post 3^b, wire 34', wire 35', switch 36' (which is to be closed) wire 37', battery 38' to the ground, thus completing the circuit. From wire 28 that part 90 of the current which does not pass through electromagnet 29 will pass down wire 33, binding post 4^a, line wire 100 back, said wire 100 being in fact, comparable with wire 32 as seen in Fig. 1, so that at stations 95

behind station 1, the magnets 29 will be energized in a manner already described but the tracing of the circuits will be in reverse order. For instance, assuming that the impulse which has been traced as far 100 as main line wire 100 is to be impressed upon line 32, the current would pass up wire 31, binding post 3^a, wire 30, electro-magnet 29, wire 28, wire 33, binding post 4^a and back to the main line from which 105 point it would go to the next station behind and to the ground there. This ground connection may be provided at the extreme rear through connections in Fig. 1 similar to 34', 35', 36', 37', 38' of Fig. 2 (assuming 110 connection 32, Fig. 1). It will be observed that magnets 27 and 29 are energized at station 1, which the train is passing, but at all other stations those magnets which correspond with 27 are idle.

When electro-magnet 27 is energized at station 1, its armature 39 will be attracted to close contact 40, whereupon current will flow from battery 41, wire 42, binding post 2^a, wire 43, armature 39, contact 40, wire 44, electro-magnet 45, wire 46, wire 47, binding post 1^a, back to the battery 41. Current flowing in this circuit will energize electro-magnet 45, which in turn will attract its armature 48, one end of which is pivoted 120 to a frame 49, and the other end of which has pivotally connected thereto a pawl 50, which pawl 50 is adapted to engage a ratchet wheel 51 rigidly connected to a tape drum 52. Trained over the drum 52 125

and a similar corresponding drum mounted in the frame 49 is a tape 53 which has printed thereon the numbers of the trains which are to pass over the system. The arrangement of the tape and the opening 54 through which the same is viewed, is such that when a train is passing the station the same will operate the tape until it discloses the number of the next train which will 5 pass the station, so that the attendant by looking through aperture 54 will be able to tell what the number of the next train will be, and knowing the schedule time of said train will be able to tell when the next train 10 is due.

When electro-magnet 29 is energized its armature 55 will be attracted to close contact 56, whereupon current will flow from battery 41, wire 42, binding post 2^a, armature 55, contact 56, wire 57, electro-magnet 58, wire 59, wire 47, binding post 1^a, back to the battery 41. Current flowing in this circuit will attract the armature 60, one end of which is pivotally connected within the 15 frame 49, while the other end thereof is pivotally connected to a pawl 61 which pawl is adapted to engage a ratchet wheel 62, which is rigidly mounted upon a drum 63, above which is trained a tape 64. The tape 64 20 which is trained around the second drum corresponding to drum 63 has printed thereon successively the names of the stations which are to be passed by the train as the latter passes over the system. By means of 25 an aperture 65 it will be possible to see the name of the various stations printed on the tape 64. The name of station which a given train is passing will appear through opening 65 at all the stations, all tapes 64 being 30 operated together. When the train passes the next station, all of the tapes will again be operated to show the name of that station. If the number of the train be 45, that 35 number will appear on the short tape 53 up to the time the train passes, when tape 53 at the station being passed will be shifted to show the number of the next train. The tape is not moved at any other station until a train passes that station, as contact 40 40 would be open. The next train will operate the several pieces of apparatus in a similar manner, assuming that the first train has passed the stations connected as above described.

When the train passes the short insulated track section it is desirable to provide some means for leaving the coherer in such a condition as to be affected when the next train passes thereby. To this end there is provided at each station a battery 66 one side of which is connected by means of wires 67 and 68 to one of the parallel sides 8 of the insulated track section whereas the other side of the battery is connected by means of wires 69 and 70 to section 9 of the insulated track 45 section. It will be obvious that so long as the train is passing the insulated track section that the rail sections 8 and 9 will be short circuited so that battery 66 will be short circuited and no current can flow 50 therefrom in an external circuit. As soon as the train leaves the sections 8 and 9, however, this short circuit is removed from the battery and current will flow from the ground through wire 14, through armature 21, through contact 23, wire 71, wire 69, battery 66, wire 67, wire 72, stationary contact 73, movable contact 74, which is connected to armature 75, through electro-magnet 76, wire 77, to the ground. This circuit will be 55 complete inasmuch as the resistance of the coherer 12 is sufficiently low to allow enough current to flow through electro-magnet 15 to keep armature 21 in contact with contact point 23. When current flows in the circuit just described the electro-magnet 76 will be energized, which will result in the attraction of one end of the armature 75, which armature is pivoted at its center and provided at the outer end with a hammer 78. As the armature 75 is attracted by the electro-magnet the hammer 78 will strike the coherer 12, so as to disturb the paths through the granular portions of the coherer to such an extent that the resistance is immediately increased. If the first blow of the hammer 78 is not sufficient the electro-magnet 15 will of course continue to be energized and contact 23 will also be closed, so that a second impulse will flow through electro-magnet 76 to 60 attract armature 75. Hence a second effort will be made by the hammer to break down the path through the coherer. This action continues until insufficient current flows through electro-magnet 15 to maintain armature 21 against contact 23.

The switches 36, one of which is located at each station, may be manually or automatically closed, the position of the switches being such that all of the switches ahead of the station which the train is passing are to be closed, whereas the switch at the station which the train is passing is to be open. The switches 36 at the stations in the rear of the station which is being passed by the train may also be closed. If, however, magnet 29 and the station tape are to be operated at given stations in the rear, as previously described, switch 36 would be closed only at the extreme rear, to effect a ground connection.

If for any reason it should be desired to energize one of the magnets 27 or 29 independently of the train, the apparatus contained within the housing 79 is provided, this apparatus comprising a pair of buttons 80 and 81. When it is desired to advance the tape giving the names of the stations one step, the button 80 is pressed inwardly, which will result in the following circuit: 65

Current will start from battery 82, pass over wire 38, binding post z^a , wire 84, contact 85, spring contact 86, binding post v^a , wire 87, wire 31, binding post 3^a , wire 30, electro-magnet 29, wire 28, wire 33, binding post 4^a , wire 88, wire 89, binding post w^a , spring contact 90, contact 91, wire 92, binding post y^a , wire 93, back to battery 82. Current flowing in this circuit will energize magnet 29, which will result in moving the tape 64 bearing the station names upwardly one step as previously described. If it be desired to advance the tape bearing the number of the next train the button 81 will be pressed instead, when current will flow from battery 82, through wire 83, binding post z^a , contact 94, spring contact 95, wire 96, binding post x^a , wire 97, wire 26, electro-magnet 27, wire 33, binding post 4^a , wire 88, wire 89, binding post w^a , wire 98, spring contact 99, contact 100, wire 92, binding post y^a , wire 93, back to battery 82. Current flowing in this circuit will energize electro-magnet 27, which will result in the energization of the magnet for advancing the tape bearing the number of the trains one step.

From the system herein described, it will be seen that a local circuit is closed by means of wireless telegraph apparatus carried by the train and that this local circuit sends impulses of low potential current over a line wire which sends impulses to the desired stations. While the description has been limited to two successive stations, yet it is to be understood that the line wires could be continued on either side of the two stations described so as to embrace a complete system.

What I claim is;

40. 1. A wireless system for train signals comprising means carried by the train to maintain a zone of influence, a stationary relay, an open circuit including said relay and responsive to the influence, means for closing said circuit when the train comes within a predetermined distance of the circuit, and means for opening said circuit when the train passes a predetermined point.
45. 2. A wireless system for train signals comprising means carried by the train to maintain a zone of influence, a stationary relay, a battery, an element responsive to the influence, a circuit including said relay, battery and element responsive to the influence, electromagnetic means to open said circuit at the responsive element, a second battery, a second circuit including said electro-magnetic means and second battery, and means to short circuit the second battery when the train approaches a predetermined point.
50. 3. A wireless signaling system for trains comprising means upon the train for maintaining a zone of influence, a coherer responsive to the influence and adapted to respond when the train is within a predetermined distance from the coherer, a relay, a battery, a circuit including said coherer, relay and battery, said circuit adapted to be closed when the coherer responds, electromagnetic means for agitating the particles of the coherer, a second battery, an insulated rail section of the track over which the train passes, a wire running from each side of the second named battery to the rails of the insulated section respectively, a second circuit including said agitating means and the second named battery, and means for closing said circuit when the relay is energized.
55. 4. In a wireless signaling system for trains, means carried by the train to set up a zone of influence, a relay, a battery, a circuit including said relay and battery, an element responsive to the influence located within said circuit adapted to close the circuit when the train is within a predetermined distance from said element, an insulated track section in the track over which the train passes, a second battery, a connection between one side of the battery and one of the rails of the insulated section, a connection between the other side of the battery and the other rail of the insulated section, means adapted to break said circuit at the element responsive to the influence, a second circuit including said second named battery and said means for breaking the circuit at the responsive element, and means controlled by the relay adapted to close said second named circuit as the relay is energized.
60. 5. A wireless system for signaling trains comprising means on the train to maintain a zone of influence, a stationary element located along the track and responsive to the zone of influence, a battery, a relay, a circuit including said responsive element, battery, and relay, an electromagnet, a second battery, means controllable by the electromagnet to interrupt the path through the responsive element, an armature controlled by the relay, a circuit including said electromagnet, said second battery, said armature when the relay is energized, and means to short circuit the second battery when the train approaches a predetermined point.
65. 6. A wireless system for signaling trains comprising means carried by the train to maintain a zone of influence, an element responsive to the influence, a battery, a relay, a circuit including said responsive element, battery and relay, a second battery, an armature for the relay, an electromagnet, means operated by the electro-magnet to interrupt the circuit through the responsive element when the electromagnet is energized, a circuit including the second battery, the armature and electromagnet designed to be closed when the relay is energized, a second

electromagnet, an armature therefor, a third electromagnet, a tape operating mechanism controlled by the third electro-magnet, a circuit including the first named armature and second electro-magnet adapted to be closed when the relay is energized, and a circuit including the third electromagnet and the armature for the second electromagnet adapted to be closed when the second electro-magnet is energized, and means to short circuit the second battery when the train reaches a predetermined point.

7. A wireless system for signaling trains, comprising means on the train to maintain a zone of influence, a stationary element adjacent to the track and responsive to the zone of influence, a battery, a relay, a local circuit including the responsive element, the

battery and relay, means to interrupt the circuit through the responsive element, a circuit controlled by said relay, a plurality of indicating tapes at the station adjacent said responsive element, means including a plurality of electro-magnets connected with said relay-controlled circuit for operating said tapes simultaneously, a plurality of tapes at a distant station and magnets controlling the tapes last mentioned, one of the last-named magnets being energized upon energizing said relay.

In testimony whereof I affix my signature in presence of two witnesses.
